UNITED STATES PATENT OFFICE.

JOHN HAYS HAMMOND, JR., OF GLOUCESTER, MASSACHUSETTS.

STEERING MECHANISM.

Application filed December 21, 1915, Serial No. 68,043. Renewed August 25, 1923.

To all whom it may concern:

Be it known that I, JOHN HAYS HAMMOND, Jr., a citizen of the United States, and a resident of Gloucester, in the county 5 of Essex and State of Massachusetts, have invented certain new and useful Improvements in Steering Mechanism, of which the following is a specification.

Some of the objects of this invention are 10 to provide improved means for steering a dirigible body, such, for instance, as a marine vessel; to provide cooperating means for propelling and steering a dirigible body, and to provide other improvements as will 15 appear hereinafter.

In the accompanying drawings, Fig. 1 is 20 a diagrammatic plan view of improved propelling and steering mechanism constructed in accordance with this invention; and Figs. 2 and 3 are fragmentary diagrammatic views of modified forms of the same.

Referring to the drawings, one embodiment of this invention comprises a dirigible body, for instance, a vessel, upon which is 25 mounted propelling and steering means including two rudders 10 and 11, and four propellers 13, 14, 15 and 16. These rudders and propellers are arranged outside of and at the stern or rear end of the vessel to 30 operate upon the water or other fluid medium supporting or surrounding the vessel. The rudders 10 and 11 are preferably rigidly secured to parallel substantially vertical rudder shafts 20 and 21, which are mounted 35 in suitable fixed bearings carried by the vessel to oscillate about their longitudinal axes respectively, and which are arranged upon opposite sides of and equal distances from a vertical plane extending longitudinally and centrally of the vessel. The propellers 13, 14, 15 and 16 are of the same 40 construction and dimensions and are rigidly secured to the outer ends of four substantially parallel shafts 25, 26, 27 and 28, which extend longitudinally of the vessel and substantially in the same plane, and which are arranged to rotate about their longitudinal axes in fixed bearings 30, 31, 32 and 33 carried by the vessel.

Two (13 and 14) of the propellers, and 45 their corresponding shafts 25 and 26 are arranged upon one side and two (15 and 16) of the propellers and their corresponding shafts 27 and 28 are arranged upon the 50 other side of a vertical plane extending longitudinally and centrally of the vessel,

the outer shafts 25 and 28 being at substantially equal distances from and upon opposite sides of the vertical central plane, and the inner shafts 26 and 27 being likewise at equal distances from and upon opposite sides of the same plane.

The propeller shafts 25, 26, 27 and 28 are arranged to be normally rotated at equal rates by four independently operated prime 60 movers 35, 36, 37 and 38, which may be of any suitable type or construction, but in the form of the invention shown, are gas engines or internal combustion engines. A tank 40 or other source of supply for holding gasoline or other hydrocarbon fluid for supplying the engines 35, 36, 37 and 38, is fixedly secured upon the vessel.

The tank 40 is connected by pipe 41 and through a carburetor 42 and a pipe 43 with 70 the outer engine 35 upon the lefthand side of the vessel, and is connected by the pipe 41, a branch pipe 45 and through a carburetor 46 and a pipe 47 with the outer engine 38 upon the right hand side of the vessel. These two carburetors 42 and 46 are provided with rotary throttle valves, which are controlled respectively by oscillatory levers 50 and 51 rigidly secured to the throttle valves respectively, whereby the 80 amount of combustible gaseous mixture which flows into the two outer engines 35 and 38 may be regulated to control or vary the speed of these outer engines.

The air tank 40 is also connected through 90 pipe 41, branch pipe 45, pipes 52 and 53 and carburetors 54 and 55 with the inner engines 36 and 37 respectively. These last mentioned carburetors may be provided with suitable throttle valves independently controlled by levers 56 and 57 whereby the speed of the inner engines 36 and 37 may be controlled or varied.

For swinging the rudders 10 and 11 simultaneously either in one direction or in the opposite direction, the rudder posts 20 and 21 are provided with bevelled gears 60 and 61 rigidly secured thereto, and which are engaged by bevelled pinions 62 and 63 which are rigidly secured respectively to the outer 100 ends of two longitudinally alined transversely extending shafts 65 and 66 which are arranged to rotate about their longitudinal axes in the fixed bearings 30, 31, 32 and 33. Rigidly secured to the inner ends of these 110 shafts 65 and 66, are two bevelled gears 70 and 71 which engage against the opposite

sides of a bevelled pinion 72, which is rigidly secured upon the outer end of a shaft 73, which extends longitudinally and centrally of the vessel and which is arranged to rotate in fixed bearings 74, 75, 76 and 77. Rigidly secured to the foremost end of this longitudinal shaft 73 is a pinion 80, which engages the underside of a transversely extending substantially horizontal rack 81 which is rigid and substantially coaxial with a piston rod 82, one end of which projects through one end of a fixed steering cylinder 83 and is rigidly secured to a piston 84 arranged to reciprocate within the cylinder. The outer end 15 of the piston rod 82 is arranged to reciprocate in a fixed bearing 85. Fluid under pressure is admitted into and exhausted from the opposite ends of the cylinder 83 through two pipes 86 and 87 which are controlled by any 20 suitable means so as to move the piston either in one direction or in the opposite direction at the will of an operator. The piston 84 is normally held in a central position in the cylinder 83 by means of two spiral springs 88 and 25 89 arranged within the cylinder and upon opposite sides of the piston 84.

For automatically reducing or varying the speed or operation of one or the other of the outer engines 35 and 38 to cooperate 30 with the rudders 10 and 11 in steering the vessel, either to the right or to the left from a given course, the throttle levers 50 and 51 controlling the speeds of the outer engines 35 and 38 are arranged to be oscillated by two 35 longitudinally aligned plungers 90 and 91 which are parallel to the piston rod 80 and which are arranged to reciprocate longitudinally in fixed bearings 92 and 93.

The outer ends of these plungers 90 and 40 91 are provided with pins 94 and 95 rigid therewith respectively, and which are slidably arranged respectively in slots 96 and 97 provided therefor in the controlling levers 50 and 51 respectively. The inner ends of 45 these plungers 90 and 91 are arranged in the paths of and to be engaged by two lugs 98 and 99 which are rigid with the rack 81. These plungers are normally held yieldingly in their innermost positions with their inner 50 ends spaced slightly from the corresponding lugs 98 and 99 by means of spiral springs 110 and 111 respectively, which connect the levers 50 and 51 with the fixed bearings 92 and 93.

55 The construction and arrangement of this improved steering mechanism is preferably such that when the means controlling the pipes 86 and 87 is so adjusted by the operator that no pressure is allowed to enter the 60 ends of the steering cylinder 83, and the rack 81 is consequently yieldingly held in a central position by the springs 88 and 89, the rudders 10 and 11 will extend substantially longitudinally of the vessel, and when 65 the engines 35, 36, 37 and 38 are rotated at

substantially equal rates, the vessel will proceed upon a straight course.

The inner ends of the plungers 90 and 91 are normally spaced at such equal distances from the lugs 98 and 99 that the rack 81 may be reciprocated independently of either of the plungers 90 and 91 through a limited path sufficient to cause the rudders to maintain the vessel normally upon a substantially fixed course without modifying the action of 75 any one of the engines or propellers.

When it is desired to steer the vessel to the right, the means for controlling the pipes 86 and 87 is adjusted by the operator to permit fluid under pressure to pass through the pipe 86 into the inner or left hand end of the steering cylinder 83, and to permit the opposite end of the steering cylinder to exhaust through the pipe 87, whereupon the rack 81 will be moved toward the right which will cause the rack 81 to rotate the pinion 80, shaft 73, pinion 72, gears 70 and 71, shafts 65 and 66, pinions 62 and 63, gears 60 and 61, and rudder shafts 20 and 21, to swing the two rudders 10 and 11 simultaneously 80 counterclockwise to steer the vessel towards the right. At the same time, this movement of the rack 81 towards the right causes the lug 99 to push the right hand plunger 91 towards the right and rotates the throttle lever 51 clockwise against the action of the spring 111, which acts by decreasing the opening of the corresponding throttle to decrease the speed of the right hand engine 38. The other three engines, 35, 36, and 37 will continue to rotate at the usual rates. By thus decreasing the speed of the right hand engine 38, the corresponding propeller 16 is retarded and acts to assist the rudders 10 and 11 in steering the boat towards the right. 90

When it is desired to steer the boat towards the left, the means for controlling the pipes 86 and 87 is adjusted by the operator to permit fluid under pressure to enter the right hand end of the steering cylinder 83, and to permit the left hand end of the cylinder 83 to exhaust through the pipe 86, whereupon the piston 84 and rack 81 will be moved outwardly thus swinging the rudders 10 and 11 simultaneously 100 in a clockwise direction through the action of the intermediate gearing. This outward movement of the rack 81 will push the left hand plunger 90 towards the left to rotate the left hand throttle lever 50 counterclockwise against the action of the spring 110, thus decreasing the speed of the left hand engine 35 to assist the rudders 10 and 11 in steering the boat towards the left. 110

Instead of having the speeds of the outer engines 35 and 38 automatically controlled by the steering piston 84 acting through throttle levers 50 and 51 as hereinbefore described, the plungers 90 and 91 might be arranged, as shown in Fig. 2, to control or 120

reduce the speeds of the outer engines 35 and 38 by retarding the times of sparking in the several cylinders of these engines. In this modified form of the invention, the 5 construction is the same as hereinbefore described, except that the plungers 90 and 91, instead of being connected to oscillate throttle levers 50 and 51 are each connected to oscillate a corresponding lever 112 which 10 controls the timing of the sparks in the cylinders of the corresponding engine 35 or 38. Each of these levers 112 may be connected in any suitable manner to perform the function of controlling the timing of 15 the sparks. For instance, each of these levers may be rigid with a sleeve 113 of insulating material arranged to rotate about a fixed axis and carrying internal contacts 114 fixed thereon and arranged to be engaged by a contact 115 which is suitably mounted to be rotated coaxially with and independently of the sleeve 113 by the corresponding engine and to engage the contacts 114 successively, whereby through well 20 known connections such as wires 120 leading from the contacts 114 to the several spark plugs 121, and a wire leading from the rotary contact through a magneto or other source of electrical energy, the sparks in the 25 several cylinders are produced at predetermined times. In the modified form of this invention, when the steering piston 84 is pushed a sufficient distance towards the left to swing the rudders 10 and 11 clockwise to steer the vessel towards the left, the left hand plunger 91 will rotate the corresponding spark lever 112 counter-clockwise to retard the sparks and correspondingly decrease the speed of the 30 35 40 45 50 55 60 65 70 75 80 85 90 95 100 both. It is also evident that instead of having the steering mechanism arranged to control only one engine or propeller upon each side of the vessel, the steering mechanism 5 might be arranged to control both engines and propellers or any number of engines and propellers either simultaneously or consecutively upon each side of the vessel.

Only a few of the various forms in which 10 this invention may be embodied have been illustrated, and it is to be understood that the invention is not limited to any specific construction, but might be applied in various ways to meet various requirements 15 without departing from the spirit of the invention or the scope of the appended claims.

Having thus fully described this invention, I claim:

1. The combination with a movable body, 20 of a plurality of independently operative propellers for actuating said body, means for steering said body, and means controlled by said steering means and operable a predetermined interval after an initial action 25 of said steering means for causing one of said propellers to rotate at a rate different from that of another of said propellers, to assist said steering means in steering said body.

30 2. The combination with a movable body, of means for propelling said body, means for steering said body, and means controlled by said steering means for modifying the action of said propelling means to assist said 35 steering means in steering said body, said steering means being initially operative within predetermined limits independently of said propelling means.

3. The combination with a movable body, 40 of a plurality of propellers for actuating said body, fluid actuated means for steering said body, and means controlled by said steering means for modifying the rate of action of one of said propellers, to assist 45 said steering means in steering said body, said steering means initially being operative

within predetermined limits independently of said propellers.

4. The combination with a movable body, 50 of means for propelling said body, means for steering said body, and means controlled by said steering means for modifying the action of said propelling means to assist said steering means in steering said body, said steering means being initially operative independently of said propelling means with in predetermined limits sufficient to maintain said body normally upon a substantially fixed course.

5. The combination with a movable body, 60 of a pair of elements carried thereby and movable with respect thereto for propelling said body, a rudder arranged to steer said body, means to independently vary the speed 65 of said propelling elements, actuating means for said rudder, and means disconnected from said actuating means but in the path of movement thereof to be engaged thereby for operating one or the other of said speed varying means simultaneously with the 70 movement of said rudder after a predetermined initial movement of said rudder actuating means.

6. The combination with a movable body, 75 of a rudder for steering said body, fluid actuated means for operating said rudder, a pair of propellers for propelling said body, driving means for said propellers, independent means for controlling the speed of said propellers, and means in the path of said rudder actuating means and arranged to be 80 engaged thereby for operating one of said speed controlling means, whereby the rate of movement of one of said propellers is varied with respect to the other.

Signed at New York city, in the county of New York and State of New York, this tenth day of December, A. D. 1915.

JOHN HAYS HAMMOND, JR.
